(57) **CLAIM**

The ornamental design for pie pan with removable access panel, as shown and described.

DESCRIPTION

FIG. 1 is a perspective view of the pie pan with the side removable access panel in the closed position;

FIG. 2 is front view of the pie pan of FIG. 1;

FIG. 3 a side view of the pie pan of FIG. 1;

FIG. 4 is a rear view of the pie pan of FIG. 1;

FIG. 5 is a top plan view of the pie pan of FIG. 1;

FIG. 6 is a bottom plan view of the pie pan of FIG. 1; and

FIG. 7 is a perspective view of the pie pan with the side access in the open position; and,

FIG. 8 is a cross-sectional view along 8–8 of FIG. 5 showing the dimension of the mating portions of the removable access panel and the pie pan body.

The removable access panel in the pie pan depicted in FIGS. 1–8 by means of broken lines forms no part of the claimed design and is provided for illustrative purposes only.
